GEARSHIFT ROLL STOP WRINGER

Nicholas L. Etten, Waterloo, Iowa

Application April 26, 1939, Serial No. 270,117

3 Claims. (Cl. 68—253)

This invention relates to clothes wringers for domestic washing machines and particularly to a safety device for stopping rotation of the rolls when roll pressure is released.

5 In cases of wringer accidents it has been found that continued rotation of the rolls is responsible for a large share of the damage arising from such accidents, and, therefore, it is equally important to stop rotation of the rolls as it is to release roll

10 pressure.

Roll stop devices as heretofore provided, have included various declutching means to stop rotation of the rolls, but in the present invention I have employed the roll drive gear in the conventional reversing gear head as a clutch member. This develops a simple, sturdy structure wherein the natural out-thrust of the drive gear is utilized to effect roll stop in a novel manner as will be disclosed in the following descriptions 15 and drawings in which:

20 Fig. 1 is a broken elevation view showing the wringer rolls under normal roll pressure and the roll drive gear in the reversing gear head in driving engagement; and

25 Fig. 2 is a similar broken elevation view showing the roll pressure released and the roll drive gear disengaged.

Now referring to the drawings in which I show a preferred embodiment of the invention, I designate the lower frame of the wringer by the numeral 10, and by the numeral 11 the upper frame. The assembled wringer structure is mounted on a wringer head 12 driven by a coupling 13 which connects to a vertical drive shaft from the wringer 30 drive mechanism. The wringer head is controlled in a conventional manner by the control handle 14.

Although I show as a preferred embodiment of 35 my invention a spur and face gear drive in the wringer head, it will be understood that this is only a preferred structure and that the conventional miter gears might be employed to obtain similar results.

40 An upper roll 15 and a lower roll 16 are mounted in the wringer frame. The top frame is held on the lower frame by a conventional integral latch 17 on its outer end and by an unstable latching device on its inner end. This unstable latch consists of a rounded projection 18 on the top frame held by a latch 19 hinged to the lower frame as 45 shown. A retaining latch 20 retains the hinged latch 19 and is controlled by a conventional release device (not shown) through the release button 21. The rolls are held in pressure engage-

ment by a conventional spring means 23 (not shown) having a pressure adjustment screw 22.

The upper roll is journaled in bearings 24 and 25. The inner end of the lower roll is journaled on a bearing 26 pivotally mounted on a cross rod 5 27. The purpose of this construction is to provide means whereby any slight misalignment of the bearing coupling 32 will be compensated for by tilting of the bearing 26 on the cross rod 27. The outer end of the lower roll is journaled in 10 a bearing 28 mounted in a steel shoe 29 having a curved upper lip 29' abutting the outer end of the lower roll shaft 16. The bearing 28 and its shoe 29 is supported on a cross member 30 having an upturned lip 31 abutting the lower edge of the shoe 15 29. The purpose of this construction will later be apparent.

The inner end 40 of the lower roll 16 is journaled in the bearing 26 which is pivotally supported by a cross pin 21. It will be appreciated 20 that by this structure any tilting of the lower roll 16 will not bind the shaft 40 in the bearing 26 because the bearing is free to pivot on the pin 27. The shaft 40 is connected to the drive gear 38 by a pin 39. I purposely make the fit of this 25 connection rather loose in order to provide play whereby the lower roll 16 may be tilted without binding. Between the bearing 26 and the inner end of the roll 16 I mount a compression spring 41 which normally urges the lower roll outward, 30 as will readily be apparent from observation of the drawings.

The reversing gear head 12 has a vertical drive shaft 32 on which is mounted the reversing gears 33 and 34. In the preferred structure as shown, 35 these gears are spur gears which normally mesh with the face drive gear 38 as shown. Although the reversing spur gears 33 and 34 are slidably mounted on the shaft 32, they may be driven by clutch contact with the pins 35 and 36 as they are raised or lowered by the eccentric pin 37 and the yoke 37' actuated by the control handle 14. This is a conventional arrangement well understood in the art, and it is not believed that any further description of the operation of the 40 reversing gear head is necessary.

45 Now referring to Fig. 2, I show the top frame just after having been released, the operator having touched the release button 21, which permits the retainer latch 20 to slide endwise, thus 50 releasing the hinged latch 19 and permitting the top frame to move upward. This upward movement of the top frame 11 is accomplished in a dual movement wherein the upper frame is tilted upward and then slides outwardly to release the 55

integral latch 17. With roll pressure released the spring 41 now forces the lower roll outward, tilting the outer bearing 28 in its shoe 29 pivoting about the vertical lip 31 of the supporting member 30. This action is further assisted by the natural outward thrust of the gear 38 in its tooth contact with the gears 33 and 34. It is well understood in the art that this outward thrust is directly proportional to the driving effort exerted by the gears and that under heavy loads the outward thrust is of considerable magnitude, and if not resisted, would result in the immediate separation and disengagement of the gears. It will, therefore, be understood that I have utilized this natural outward thrust of the gears to effect disengagement and roll stop in a natural and effective manner. It will be appreciated that in this movement the entire lower roll and shaft is the sliding member and it is of such length that no binding friction will be developed. This is quite a different structure from small, short clutch couplings wherein such binding action is much more liable to occur than in my structure where the entire lower roll shaft is the movable member. Further, it will be appreciated that the upward tilting movement of the bearing 28 has very little binding effect and this likewise contributes to the effectiveness of my device.

When the upper frame is again latched on the lower frame and roll pressure restored, it will readily be appreciated that the lower roll, pivoting inward on the tilted bearing 28, will move easily with a minimum of interference to again effect engagement of the drive gear 38 with the reversing gears 33 and 34.

In general, I have provided a structure wherein the fewest possible number of parts are employed and the clutching element of the roll stop is the driven gear in the reversing gear head mounted on the driven roll shaft. This structure employs not only the fewest number of parts, but the length of the moving member, namely, the entire driven roll is such that it is very much less liable to bind and otherwise become inoperative than any structure wherein smaller and shorter

clutch elements are employed. Further, it will be apparent that in employing the outward thrust of the drive gear to effect disengagement of the gears and roll stop, I am employing a natural force that is increased in proportion to the driving effort and thus becomes more effective as the need for disengagement is increased.

Having thus described my invention,

I claim:

1. In a wringer, a reversing gear head drive, a frame, a pair of cooperative pressure rolls, roll pressure release and reset means, a drive gear of the gear head attached to the driven roll, said drive gear being held in driving relationship in the gear head by said driven roll and removed from driving relationship by longitudinal movement of the driven roll, and means to move the driven roll to effect disengagement of the drive gear when roll pressure is released and to effect reverse movement and gear engagement when roll pressure is restored.

2. In a wringer, a reversing gear head drive, a frame, a pair of cooperative pressure rolls, roll pressure release and reset means, a drive gear of the gear head attached to the driven roll, said drive gear being held in driving relationship in the gear head by said driven roll and removed from driving relationship by longitudinal movement of the driven roll, and a tilting outer bearing on the driven roll co-acting with the outward thrust of the drive gear and a compression spring to effect disengagement of the drive gear when roll pressure is released and to effect reverse movement of the driven roll and gear engagement when roll pressure is restored.

3. In a wringer, a reversing gear head drive, a frame, a pair of cooperative pressure rolls, roll pressure release and reset means, a drive gear of the gear head attached to the driven roll, and means to effect longitudinal movement of the driven roll and drive gear whereby the drive gear is disengaged when roll pressure is released and by reverse movement to effect gear engagement when roll pressure is restored.
